UNITED STATES PATENT OFFICE.

ENOCH S. YENTZER, OF OTTAWA, ILLINOIS.

IMPROVEMENT IN PANTALOON-STAYS.

Specification forming part of Letters Patent No. **155,566**, dated September 29, 1874; application filed August 24, 1874.

To all whom it may concern:

Be it known that I, E. S. YENTZER, of Ottawa, county of La Salle, State of Illinois, have invented certain Improvements in Supporters for Pantaloons, of which the following is a specification:

The object of my invention is to give pantaloons-legs more stiffness and a better form, and make them to present a less bulky appearance than can be done by the present mode of placing a canvas lining inside around the bottom of the leg.

My invention consists in attaching a supporter, made of canvas, hair-cloth, or other suitable material, having the form of a conical section, to the side seams of the pantaloons bottoms. The supporters are sewed to the seams with the base downward, in such a manner that the base extends equally on both sides of the seam, and running up the seam to a point where it is fastened to the same, the points of the base being fastened to the inside of the material itself, or to its lining.

In order to describe my invention more fully, I refer to the accompanying drawing forming a part of this invention.

Figure I is a side view of the inside half of a pantaloons-leg. Fig. II is a side view of the inside other half of a pantaloons-leg. Fig. III is a detached plan view of one of the supporters.

A represents the leg of a pair of pantaloons. b and c represent the outside and inside seams of the leg A. D is the outside support, and E the inside.

Having described my invention, I claim—

The pantaloons-leg stays D and E, constructed and arranged substantially for the purpose hereinbefore set forth.

ENOCH S. YENTZER.
